(57) **CLAIM**

The ornamental design for "slabbed log", as shown and described.

DESCRIPTION

FIG. 1 is a perspective view of a first embodiment of the design.

FIG. 2 is a plan view of a first embodiment of the design.

FIG. 3 is a side view of a first embodiment of the design.

FIG. 4 is an end view of a first embodiment of the design.

FIG. 5 is a perspective view of a second embodiment of the design.

FIG. 6 is a plan view of a second embodiment of the design.

FIG. 7 is an end view of a second embodiment of the design.

FIG. 8 is a side view of a second embodiment of the design.

FIG. 9 is a perspective view of a third embodiment of the design.

FIG. 10 is a plan view of a third embodiment of the design.

FIG. 11 is a side view of a third embodiment of the design.

FIG. 12 is an end view of a third embodiment of the design.

FIG. 13 is a perspective view of a fourth embodiment of the design.

FIG. 14 is a plan view of a fourth embodiment of the design.

FIG. 15 is an end view of a fourth embodiment of the design.

FIG. 16 is a side view of a fourth embodiment of the design.

FIG. 17 is a perspective view of a fifth embodiment of the design.

FIG. 18 is a plan view of a fifth embodiment of the design.

FIG. 19 is a side view of a fifth embodiment of the design.

FIG. 20 is an end view of a fifth embodiment of the design.

FIG. 21 is a perspective view of a sixth embodiment of the design.

FIG. 22 is a plan view of a sixth embodiment of the design.

FIG. 23 is a side view of a sixth embodiment of the design.

FIG. 24 is an end view of a sixth embodiment of the design.

FIG. 25 is a perspective view of a seventh embodiment of the design.

FIG. 26 is a plan view of a seventh embodiment of the design.

FIG. 27 is a side view of a seventh embodiment of the design.

FIG. 28 is an end view of a seventh embodiment of the design.

FIG. 29 is a perspective view of a eighth embodiment of the design.

FIG. 30 is a plan view of a eighth embodiment of the design.

FIG. 31 is a side view of a eighth embodiment of the design.

FIG. 32 is an end view of a eighth embodiment of the design.

FIG. 33 is a perspective view of a ninth embodiment of the design.

FIG. 34 is a plan view of a ninth embodiment of the design.

FIG. 35 is a side view of a ninth embodiment of the design; and,

FIG. 36 is an end view of a ninth embodiment of the design. The slabbed log has been broken in the center to indicate indeterminate length.
